UNITED STATES PATENT OFFICE

RALPH D. STURM, OF OAKLAND, CALIFORNIA, ASSIGNOR TO HAZEL-ATLAS GLASS CO., OF WHEELING, WEST VIRGINIA, A CORPORATION OF WEST VIRGINIA

LEER LOADER

Application filed January 26, 1931. Serial No. 511,871.

The present invention relates to leer loaders and has for its primary object the provision of means for steadyng glassware as it is being transferred to the traveling conveyer of an annealing leer, and especially to such means as are adaptable for use with a leer loader of the reciprocating stripper bar type.

A further object of the invention is the provision of a simple and inexpensive yet efficient means for cooperation with a leer loader to steady the ware being transferred to the leer conveyer, which means is adjustable to adapt it to ware of varying sizes.

A still further object of the invention consists in providing a replacer element attached to an operating part of the ware-steadying means, whereby any piece of ware which may inadvertently reach a position beyond the end of the stripper bar will be automatically brought back into the path of operation of the bar.

Other objects and advantages of the invention will appear from the following description when taken in connection with the accompanying drawings, in which

Figure 1 is a perspective view of the front end of a leer provided with a leer loader and the ware steadyng device attached thereto.

Figure 2 is a horizontal section through the front end of the leer and showing the leer loader and steadyng device associated therewith.

Figure 3 is a fragmentary sectional view taken on line 3—3 of Figure 2; and

Figure 4 is an enlarged detail view of a portion of the pusher bar and the ware steadyng mechanism mounted thereon.

The leer loader with which the present improvements are illustrated is substantially identical with that shown in the application of Arthur Covey for patent on mechanism for transferring glassware from forming machines to leers, Serial No. 462,564, filed June 20, 1930. The leer loader will first be briefly described and then the improvements will be described in more detail, but it is to be understood that the present invention is not limited to use with the particular leer loader with which it is shown associated.

Numerol 1 designates a leer which is provided with the usual conveyer 2, and shadow pan 3. The loading device is mounted on one side only of the leer, and comprises a stripper bar 5 and a rod 6, to which one end of the stripper bar is secured.

The rod 6 is mounted so as to be reciprocated back and forth along its axis and also to be tilted to raise and lower the stripper bar 5. For this purpose, a frame 7 is tiltably mounted on one side of the leer, as indicated by numeral 8, and is provided with pairs of roller bearings 9 through which the rod 6 is reciprocated back and forth. The pivot 8 is supported on a bracket 10, and also mounted on this bracket is an extension or arm 11 provided with an upwardly extending screw or bolt 12, which may be vertically adjusted by means of nuts 13. The forward end of the frame 7 carries a counterbalance weight 14 which serves to normally return the frame 7 to a substantially horizontal position with the forward end of the frame resting upon the top of the bolt 12.

The stripper bar 5 is supported at one end only, namely, that end which is secured to the reciprocating rod 6; and in order to prevent the bar from sagging, means is provided on the rod for cooperation with the frame 7 to resist any torque set up in the rod. This means comprises a pin 15 extending downwardly through rod 6 and provided with a roller 16 on its lower end. This roller is adapted to ride back and forth in guideway 17 formed upon the upper surface of frame 7, thereby providing a strong and efficient means for retaining the stripper bar 5 in a horizontal position at all times.

For reciprocating the rod and stripper bar, there is provided a crank arm 18 which is driven through reduction gearing 19 by means of an electric motor 20; these elements being supported on the side of the leer by means of the brackets 21. Reciprocating movement is imparted to the rod 6 by means of a connecting rod 22 which is pivotally connected to the crank 18, as indicated by numeral 23; its opposite end being pivotally connected to the rod 6, as indicated by numeral 24. This connecting rod 22 is of the

turnbuckle type and thus provides means for varying the extreme limits of movement of the stripper bar toward and from the mouth of the leer.

5 To provide means for tilting the rod 6 and thus raising and lowering the stripper bar 5, to effect proper movements thereof to avoid oncoming ware, the crank arm 18 is provided with a roller 25 on that side of the crank arm 10 adjacent the rod 6. After the crank arm 18 has rotated rearwardly in the direction of the arrow to feed the ware to the leer, the roller 25 will engage the adjacent end of the rod 6. This engagement of the roller 25 with 15 rod 6 will depress that end of the rod and thus cause the frame 7 to be rocked upon its pivot 8 thereby raising the stripper bar so that it may clear the top of the oncoming ware as the bar is moved backward to its initial position. It should be noted in this connection that the roller 25 is positioned to one side of the line passing through the pivot 23 of the connecting rod and the center of rotation of the crank arm 18. By means of this 20 particular positioning of the roller 25 with respect to the pivot point 23 of the connecting rod, it will be apparent that the roller will not engage the rod until after pivot 23 has passed below the horizontal plane of rod 6. 25 Accordingly, a slight rearward movement will be imparted to the rod prior to the initiation of the downward movement of the end thereof, with the result that the stripper bar 5 is backed away a slight distance from the ware which has been moved into the leer, before the stripper bar is raised, thus avoiding 30 any tendency to displace or upset the ware.

It is also desirable to vary the height to which the stripper bar is raised in its return movement, and for this purpose the roller is 40 mounted in a slot 26 extending toward the pivot of crank arm 18, and may be clamped at any desired position within the slot, thereby varying the effective length of the crank arm, and thus varying the extent of upward 45 movement of the stripper bar.

Before describing the operation of this particular loading device, I shall first describe the rotary table, and the mechanism for rotating the table.

50 Numeral 27 refers to a base member upon which the leer rests. This base member has a forward extension upon which rests a frame 28 carrying a bracket 29 in which is rotatably mounted the shaft 30 of a table 31, the latter lying flush with the shadow pan 3. Thus the leer, the loader, the rotary table and its operating mechanism constitute a single unit which may be moved to any desired position relative to a forming machine. 55 The base member may be provided with rollers if desired, to assist in properly positioning it in the plant.

The shaft 30 carries at its lower end a bevel gear 32 meshing with a bevel gear 33 60 on a horizontal shaft 34. Also fixed to this

shaft 34 is a sprocket wheel 35 driven from a sprocket wheel 36 on a shaft 37, by means of a sprocket chain 38. This shaft 37 extends rearwardly along the side of the leer; being mounted in suitable bearings attached to the side of the leer. The rear end of this shaft is provided with a bevel gear 39 meshing with a similar gear 40 on a shaft 41. The shaft 41 also has fixed thereto a sprocket wheel 42, driven by a sprocket wheel 44, through a sprocket chain 43. The sprocket wheel 44 is driven by the reduction gearing 19, so that the motor 20 drives both the unloading device and the table; the stripper bar of the unloading device being continuously reciprocated and the table being continuously rotated.

The unit, consisting of the leer, the rotary table, the stripper bar and the mechanism for operating the table and bar, is so positioned that the table will be in cooperative relation with a forming machine. The particular position of the table with respect to the forming machine is not important, providing it is close enough to the forming machine to permit the ordinary take-out device to remove the finished articles from the molds at the delivery position and deposit them on the table. It is immaterial at what point around the periphery of the table the articles are deposited.

The articles, being placed on the table one by one, are carried around by the table until they are brought in front of the leer. At the proper instant the stripper bar will operate to sweep the articles in front of it, forward onto the leer conveyer 2. If the articles are being placed on the rotary table at a point somewhere near the leer front, then only two or three of the articles may remain on the table after each operation of the stripper bar, and those few remaining will, of course, continue their travel until they are in front of the leer ready to be carried forward by the stripper bar. On the other hand, if the articles are being placed on the rotary table at a point remote from the leer front, then it is apparent that there will be a long string of articles on the table at all times, a certain number of which are swept forward into the leer with each operation of the stripper bar. So it is apparent that the articles may be placed on the table near the leer front, remote therefrom, or at any intermediate and convenient point. Of course, the stripper bar does not extend all the way across the table, unless the diameter of the table happens to be substantially equal to the width of the leer conveyer. Usually the table is much wider than the leer conveyer, as in the specific form illustrated herein, and the stripper bar is of such length that its free end is just about in alignment with the far side of the leer conveyer.

A brief description of the operation of the

stripper and its mechanism, will now be given; it being understood that the invention is not limited to this particular loading device.

- 5 When the loader is put into operation, the bolt 12 is adjusted vertically so as to properly position the stripper bar 5 with respect to the particular ware which is being made on the forming machine, thereby accom-
10 modating the leer loader to the center of gravity of the ware; the turnbuckle 22 is ad-
justed to properly fix the limits of move-
ment of the stripper bar, and the roller 25
is moved to that position in slot 26 which best
15 adapts the device to the particular size of
ware being handled. As described herein-
before, the loading device and the rotary
table are operated by the motor 20, so that
their movements are synchronized; the speed
20 of operation being controlled by the motor
and the reduction gearing. The parts are so
timed that when the table has rotated to
bring in front of the leer a line of ware sub-
stantially equal to the width of the leer tun-
25 nnel, the stripper bar will operate to draw the
string of ware off the rotating table, across
the shadow pan 3, and onto the leer conveyer
2; which will carry it slowly forward through
the leer.
30 After the ware is brought onto the leer con-
veyer 2, the crank arm 18 will pass below the
horizontal plane of its pivot point and cause
the stripper bar to back away slightly from
the ware, just before the roller 25 engages
35 the rod 6. While the roller 25 is depressing
the end of the rod 6, the rearward movement
of the rod will also be continued due to the
rotary movement of the crank arm 18. Thus
the stripper bar will follow an arcuate path
40 in its cycle of operations. As the crank arm
rises, roller 25 will allow the stripper bar to
gradually descend to its initial position, pro-
jecting across a portion of the rotating table.
In the meantime, the rotation of the table
45 has carried another string of ware into posi-
tion in front of the leer and the continued ro-
tation of the crank arm 18 will again operate
the stripper arm to sweep the string from the
table onto the leer conveyer; the reciproca-
50 tion of the stripper bar and the rotation of the
table continuing as long as the forming ma-
chine is in operation. It will be noted that
from the time the articles are taken from the
molds until they are in the annealing leer,
55 they are subjected to only one movement rela-
tive to the surfaces upon which they are
supported, which is when they are swept for-
ward by the stripper bar from the table to
the leer conveyer.
60 The attachments for steadyng the ware
being pushed into the leer and the replacer
bar for returning into alignment with the
leer conveyer any ware which may have been
65 accidentally carried beyond the line of travel
of the leer conveyer will now be described.

Bolted onto the top of the stripper bar 5 is a T-bar 50 which provides a track on which is slidably mounted a plate 51. This plate is slidably mounted on the track by means of fingers or lugs 52 secured by bolts 53. These bolts also extend through brackets 54 and 55 and serve to secure these brackets on the plate for a purpose to be hereinafter de-
scribed.

Secured on top of the plate 51, as by bolts 56 and spacer thimbles 57, is a bearing mem-
ber or block 58. Pivotaly mounted in the
member 58 is a shaft 59; this shaft being
provided at one end with a crank arm 60 and
being squared at its opposite end to receive
a sleeve 61 which may be adjustably secured
thereon by means of a set screw 62. Mounted
in the member 61 is a ware steadyng arm 63
which may be removably secured therein as
by means of screw 64.

The plate 51 is normally drawn toward one
end of the track 50 by a coil spring 65 hav-
ing its ends secured to the plate and to the
T-bar by hooks 65' and 65'', respectively. In
order to limit the movement produced in the
plate by means of the spring 65, a stop plate
66 is secured to the T-bar and serves as an
abutment for the plate 51. Pivoted to the
crank arm 60 is a link 67 which has its op-
posite end pivoted to a bracket 68 mounted
on the adjacent end of the T-bar. The plate
51 and the parts carried thereby are adapted
to be moved toward the center line of the
leer as the stripper bar is moved toward the
leer conveyer, and for this purpose a cam
track 69 is mounted to one side of the leer,
as shown more clearly in Figures 1 and 2.
Cooperating with the cam track 69 is a cam
roller 70 carried on a pin 71 fixed to the brack-
et 55. As the roller 70 engages the inclined
portion of the cam track 69 it will be apparent
that the plate 51 will be moved toward the
center line of the leer against the tension of
spring 65. In this movement of the plate
toward the center line of the leer the shaft
59 will be rotated about its axis by reason of
the fact that the link 67 which has one end
pivotally connected to the crank arm 60, re-
mains stationary while the plate 51 and shaft
59 are moved toward the center line of the
leer. This rotation of the shaft 59 will cause
the ware steadyng arm 63 to move from its
upwardly inclined position as shown in Figs.
1 and 4, to a substantially horizontal position,
as indicated in dotted line in Fig. 2; thus
being brought into a position adjacent the
line of ware being pushed onto the leer con-
veyer by the stripper bar 5.

Mounted on the bracket 54 also carried by
the plate 51 is a block of asbestos or other
similar material 72. At each movement of
translation of the plate 51 toward the center
line of the leer this block 72, which serves as a
replacer bar, will act to bring into alignment
with the leer conveyer any piece of ware

which may have accidentally been carried to one side of the line of travel of the leer conveyer.

In the operation of the device the ware steadyng arm 63 is adjusted by means of the set screw 62 to a position relative to the stripper bar 5 which best suits it to the particular dimensions of ware being annealed, and the leer loader is then set in operation 10 as hereinbefore described. After the cam roller 70 reaches the track 69, the plate 51 is moved toward the center line of the leer and in doing so causes the ware steadyng arm 63 to assume a position parallel to the stripper bar 5. Thus the line of ware being pushed over is entirely eliminated.

Just before the stripper bar reaches the 20 limit of its inward movement the cam roller 70 should pass the end of the cam track 69 and cause the plate 51 to return automatically to its original position by means of the spring 65, thereby causing the link 67 to return the 25 crank 60 to its original position and thus raise the ware steadyng arm 63 to an inoperative position as indicated in Figs. 1 and 4. This return of the ware steadyng arm 63 to the inoperative position has thus taken place 30 before the slight return movement of the stripper bar and also before the stripper bar is raised by operation of the roller 25, as hereinbefore mentioned. In this movement of the plate 51 back and forth along the stripper 35 bar 5 the replacer bar 72 will operate to re-align with the leer conveyer any piece of ware which has been inadvertently carried beyond the line of movement of the leer conveyer.

From the above description taken in connection with the attached drawings it will be 40 apparent to those skilled in the art that I have provided a very simple attachment for leer loaders, and especially those of the stripper bar type, which automatically operates to 45 steady the ware as it is being transferred to the leer conveyer; that it is adjustable to varying sizes of ware; and that the means provided very readily adapts itself to the provision of a replacer bar for re-aligning 50 ware with the leer conveyer.

While the improvements shown and described herein are illustrated in conjunction with a particular leer loader, it is to be understood that the invention is not so limited and 55 may, with slight modification, be adapted for use with a variety of constructions used for feeding ware into an annealing leer.

In accordance with the patent statutes I have described the preferred construction of 60 my invention, but various minor changes may be made in the details of construction without departing from the spirit of the invention, and all such modifications are intended to be included within the scope of the 65 appended claims.

What I claim is:

1. A leer loader including a stripper bar, a ware-steadyng arm slidably and pivotally connected to the bar, means for moving the bar toward and from the leer, and means for sliding and swinging the arm to ware-steadyng position as the bar is moved toward the leer.

2. A leer loader including a stripper bar, a ware-steadyng arm slidably and pivotally 75 connected to the stripper bar, a replacer bar slidably mounted on the stripper bar, and means for moving the arm and replacer bar to operative position as the stripper bar is moved toward the leer.

3. A leer loader including a stripper bar, a member slidably mounted on the stripper bar, a ware-steadyng arm pivoted on said member, means for moving said member longitudinally of the stripper bar, a crank arm 85 on said pivot, and a link connecting the crank arm with said stripper bar, whereby the ware-steadyng arm is moved to operative position as the slidable member is caused to move relatively to the stripper bar.

4. A leer loader including a stripper bar, a member slidably mounted on the stripper bar, a ware-steadyng arm pivoted on said member, a replacer bar fixed to said member, means for moving said member longitudinally of the stripper bar, a crank arm secured 95 to the pivot of said ware-steadyng arm, and a link connecting the crank arm with said stripper bar.

5. A leer loader including a stripper bar, a member slidably mounted on the stripper bar, a ware-steadyng arm pivoted on said member, means for moving said member longitudinally of the stripper bar, and means for causing said ware-steadyng arm to 105 swing about its pivot as said member is moved along the pusher bar.

6. A leer loader including a stripper bar extending across the front of a leer, a ware-steadyng arm pivotally mounted at one of its ends only at one side of the leer, means for moving the stripper bar toward and from the leer, and means for swinging the ware-steadyng arm downwardly from one side of the leer into substantially the plane of the 110 stripper bar.

7. A leer loader including a stripper bar extending across the front of a leer, means for moving the stripper bar toward and from the leer, a ware-steadyng arm mounted on the stripper bar, means for moving the ware-steadyng arm back and forth longitudinally of the stripper bar, and means for moving the ware-steadyng arm into and out of the 115 horizontal plane of the stripper bar.

8. A leer loader including a stripper bar extending across the front of a leer, means for moving the stripper bar toward and from the leer, a ware-steadyng arm mounted on the stripper bar, a replacer member mounted 120

on the stripper, means for periodically moving the ware-steadying arm into the horizontal plane of the stripper bar to steady ware about to be transferred, and means for moving the replacer member longitudinally of the stripper bar to replace ware in proper alignment for transfer.

9. A leer loader including a stripper bar extending across the front of a leer, means for moving the stripper bar toward and from the leer, a ware-steadying arm mounted on the stripper bar, a replacer member mounted on the stripper bar, means for moving the ware-steadying arm and the replacer member back and forth longitudinally of the stripper bar, and means for moving the ware-steadying arm into and out of the horizontal plane of the stripper bar.
